(57) **CLAIM**

The ornamental design for a star-shaped package, as shown and described.

DESCRIPTION

FIG. 1 is a perspective view of a new design for a star-shaped package;

FIG. 2 is a plan view, the opposite plan view being a mirror image thereof;

FIG. 3 is a view taken in the direction of Line 3—3 in FIG. 2, such that the five views taken at 60 degree intervals around the circumference of the package are identical; and, FIG. 4 is a view taken in the direction of Line 4—4 in FIG. 2, such that the five views taken at 60 degree intervals around the circumference of the package are identical.
